UNITED STATES PATENT OFFICE.

GUSS A. MILLER, OF NUMA, IOWA.

SEWING-MACHINE.

1,258,594.

Specification of Letters Patent.

Patented Mar. 5, 1918.

Application filed August 25, 1917. Serial No. 188,160.

To all whom it may concern:

Be it known that I, GUSS A. MILLER, a citizen of the United States, residing at Numa, in the county of Appanoose and State of Iowa, have invented new and useful Improvements in Sewing-Machines, of which the following is a specification.

This invention relates to sewing machines of the lock-stitch type.

10 The invention has for its object to produce a device of the class described which will be simple in construction, efficient in operation, and which may be produced at a very moderate expense.

15 A further object of the invention is to simplify and improve the construction of the frame as well as that of the sewing mechanism supported and guided in said frame.

20 A further object of the invention is to simplify and improve the construction and arrangement of the thread supporting and guiding means.

25 A further object of the invention is to simplify and improve the construction and arrangement of the presser foot.

With these and other ends in view which will readily appear as the nature of the invention is better understood, the same consists in the improved construction, novel 30 arrangement and combination of parts which will be hereinafter fully described and particularly pointed out in the claims.

In the accompanying drawings has been illustrated a simple and preferred form of 35 the invention, it being, however, understood that no limitation is necessarily made to the precise structural details therein exhibited, but that changes, alterations and modifications within the scope of the claims may be 40 resorted to when desired.

In the drawings,

Figure 1 is a side view of the improved sewing machine, the cover plate having been detached.

45 Fig. 2 is a view similar to Fig. 1 but showing the needle bar in a lowered position.

Fig. 3 is a vertical sectional view on the line 3—3 in Fig. 1, but with the cover plate 50 in position.

Fig. 4 is a sectional detail view taken on the line 4—4 in Fig. 1.

Fig. 5 is a perspective detail view showing the shuttle bar and holder detached.

Fig. 6 is a perspective detail view of the 55 shuttle.

Corresponding parts in the several figures are denoted by like characters of reference.

The frame structure of the improved device may be described as consisting of a flat hollow casing embodying a base portion 15, an upright portion 16 at one end of the base and a top portion or arm 17, the latter being preferably inclined in an upward direction with respect to the upright and the base. The base, the upright and the top arm 17 are provided along their side edges with forwardly extending flanges 18 adapted to support the cover plate 19 which may be 60 assembled with the body of the casing by machine screws 20 for the reception of which suitable apertures are provided, the said cover member coöperating with the body portion of the base to form a hollow casing 65 of proper dimensions to receive the operating parts of the device.

The top arm 17 is provided with a vertically disposed sleeve 20' through which the needle bar 21 is guided for vertical reciprocatory movement, said needle bar being preferably of square cross section to prevent it from turning in the sleeve. Secured on the upper end of the needle bar is a hollow hand piece 22 which is adapted to contain 80 a spool of thread 23, a slot 24 being formed through which the thread may be drawn from the spool. The lower end of the needle bar has a socket 25 for the reception of a 85 needle 26 which may be an ordinary stout sewing machine needle, the same being secured in the socket by means of a set screw 27. A thread guide 28 is attached to the hand piece 22. Other thread guides 29 are mounted on the sleeve 20' of the casing and 90 still another thread guide 30, the latter in the nature of a coiled spring, is connected with the lower end of the needle bar, said spring surrounding the needle so as to guide the thread closely adjacent thereto. Secured on 95 the flange 18 at the lower end of the top arm 17 is a bracket 31 on which is adjustably mounted a sleeve 32 carrying a presser foot 33, said slide being retained in adjusted position on the bracket 31 by a set screw 34, 100 thus enabling the presser foot to be readily adjusted according to the thickness of the material that is to be operated upon.

105

The base portion 15 of the frame structure has a longitudinal groove 35 wherein the shuttle bar 36 is guided for reciprocatory movement, said shuttle bar being formed 5 with a holder 37 for the shuttle 38 and said shuttle bar being also provided with a spring 39 to retain the shuttle in position. The shuttle is of ordinary construction and is adapted to contain a bobbin 40. The 10 thread coming from the bobbin is guided through a slot 41 in the side of the shuttle and beneath a tension spring 42.

The shuttle bar is provided adjacent to one end thereof with an anti-friction element such as a roller 43 which is engaged 15 by a fork 44 formed on an arm 45 which extends downwardly from a lever 46 which is fulcrumed within the casing on the arm 17, said lever being provided with a longitudinal slot 47 engaging the fulcrum member 48 so as to permit the said lever to have a limited sliding movement. One arm of 20 the lever 46 engages a slot or recess 49 in the needle bar so that by moving the latter up and down the lever will be rocked about its fulcrum and will serve to produce a reciprocatory movement of the shuttle bar which will be properly timed to withdraw 25 the shuttle from beneath the needle when the latter descends and to advance the shuttle when the needle is retracted.

The cover member 19 is provided with a slide 50 which is readily removable so as to afford access to the shuttle whenever desired.

The flange portion 18 at the top edge of the base portion of the frame or casing is provided with an opening 55 for the passage 40 of the needle in order that the looped portion of the thread may be carried within the casing to be engaged by the shuttle in the usual and well understood manner. There has also been shown a clip plate 56 which is attached to the base portion 15 45 within the casing by means of screws 57, said clip plate overlapping the shuttle carrying bar for the purpose of retaining the latter in the groove 35 wherein it is arranged for reciprocation.

50 From the foregoing description taken in connection with the drawings hereto annexed the operation and advantages of this invention will be readily understood by those skilled in the art to which it appertains. The device may be used for sewing and mending shoes, harness and other leather goods as well as for sewing sacks and the like and it is in fact useful for a great 55 variety of purposes which will readily suggest themselves. The material that is to be operated upon is supported on the base portion of the frame beneath the presser foot, the latter being properly adjusted to suit the thickness of the material that is to be 60 operated upon. By forcing the needle down-

wardly through the goods and subsequently retracting the same, a lock stitch will be formed by the conjoint operation of the needle and the shuttle. After the formation of one stitch, the device is adjusted with 70 respect to the goods (or vice versa) to the proper position for forming the next stitch, after which the operation is repeated as will be readily understood. The construction and operation of the improved device 75 is extremely simple and the device is thoroughly useful for the purposes for which it is intended.

What is claimed, is:

1. In a device of the class described, a 80 hollow casing having a detachable cover plate embodying a base portion having a longitudinal groove, an upright and an arm extending from the upright and having a terminal vertical sleeve, a needle bar guided 85 in the sleeve having a needle socket at its lower end, a needle adjustable in said socket, a hollow hand piece at the upper end of the needle bar adapted to receive a spool of thread, said hand piece having a slot for the 90 passage of thread, thread guides on the hand piece, the casing and the needle bar, a presser foot associated with the casing, a shuttle carrying bar guided in the longitudinal groove in the base portion of the casing, and means within the casing for transmitting motion from the needle bar to the shuttle carrying bar.

2. In a device of the class described, a 100 hollow casing having a detachable cover plate embodying a base portion having a longitudinal groove, an upright and an arm extending from the upright and having a terminal vertical sleeve, a needle bar guided 105 in the sleeve having a needle socket at its lower end, a needle adjustable in said socket, a hollow hand piece at the upper end of the needle bar adapted to receive a spool of thread, said hand piece having a slot for the 110 passage of thread, thread guides on the hand piece, the casing and the needle bar, a presser foot associated with the casing, a shuttle carrying bar guided in the longitudinal groove in the base portion of the casing, and means within the casing for 115 transmitting motion from the needle bar to the shuttle carrying bar, said means comprising a lever fulcrumed within the casing on the arm thereof and also capable of a limited slidable movement, said lever having a downwardly extending arm provided with a terminal fork engaging an anti-friction member on the shuttle carrying bar and said lever having also an arm engaging the recess with which the needle bar is provided.

3. In a device of the class described, a casing, a needle bar supported for vertical reciprocatory movement, a hollow hand piece for said needle bar, said hand piece having a 130

- slot and said hand piece constituting a receptacle for a spool of thread, said thread being guided through the slot, thread guides on the hand piece and on the casing, a needle connected with the needle bar, and an additional thread guide consisting of a spring connected with the needle bar and coiled about the needle.
4. In a device of the class described, a casing embodying a base portion, an upright, an arm extending from the latter and having a terminal sleeve, a needle bar guided for reciprocation in said sleeve, a shuttle carrying bar mounted for reciprocation 15 within the casing on the base portion of the latter, means within the casing for transmitting motion from the needle bar to the shuttle carrying bar, a bracket mounted on the arm of the casing, and a sleeve adjustably supported on said bracket and having a presser foot extending in the direction of the base.
5. In a device of the class described, a casing, a needle bar guided for reciprocation, said needle bar having externally of 25 the casing a hollow hand piece adapted to receive a spool of thread, means for guiding the thread externally of the casing, a shuttle bar guided for reciprocation substantially at right angles to the needle bar
- 30 substantially at right angles to the needle bar

and means within the casing for transmitting motion from the needle bar to the shuttle bar.

6. In a device of the class described, a casing, a needle bar guided for reciprocation, said needle bar having externally of 35 the casing a hollow hand piece adapted to receive a spool of thread, means for guiding the thread externally of the casing, a shuttle bar guided for reciprocation substantially 40 at right angles to the needle bar and means within the casing for transmitting motion from the needle bar to the shuttle bar, said means comprising a lever fulcrumed within the casing and capable of a limited slidable 45 movement.

7. In a device of the class described, a casing, a needle bar guided for reciprocation, said needle bar having externally of 50 the casing a hollow hand piece adapted to receive a spool of thread, means for guiding the thread externally of the casing, a shuttle bar guided for reciprocation substantially 55 at right angles to the needle bar and means within the casing for transmitting motion from the needle bar to the shuttle bar, said needle bar and hand piece being equipped with thread guides.

In testimony whereof I affix my signature.
GUSS A. MILLER.
